(57) **ABSTRACT**

An inkjet recording device including: inkjet head having a pressure chamber; a first pressure source to adjust ink energy per unit volume to generate “energy per unit volume” P1(Pa) relative to static ink at an atmospheric pressure at a nozzle opening height; a second pressure source to adjust ink energy per unit volume to generate “energy per unit volume” P2(Pa) relative to static ink; and a hardware processor. The first pressure source, pressure chamber, and second pressure source are connected in this order by a flow path. Assuming that a pressure loss occurring from the first pressure source to the nozzle due to circulation flow rate is ΔP_a , a proportionality constant of a differential pressure (P1-P2) and ΔP_a is “a”, and an appropriate pressure in vicinity of the nozzle opening is Pn, the hardware processor controls pressure to establish $P2 = \{Pn - (1-a)P1\}/a$.

CROSS REFERENCE TO RELATED APPLICATIONS

This is the U.S. national stage of application No. PCT/JP2020/000650, filed on Jan. 10, 2020. Priority of which is claimed and is also incorporated herein by reference.

TECHNICAL FIELD

The present invention relates to an inkjet recording device and a manufacturing method thereof.

BACKGROUND ART

Existing inkjet devices are known to circulate ink through an inkjet head and to eject the ink from a nozzle of the inkjet head.

According to the invention disclosed in Patent Document 1, the pressure of ink in the vicinity of the opening of a nozzle is maintained at an appropriate pressure as follows. That is, an appropriate pressure (P_n) of the ink in the vicinity of the opening of the nozzle is made at the atmospheric pressure or lower by maintaining a relation of a pressure source (P_1) on an upstream side, a pressure source (P_2) on a downstream side, and the appropriate pressure (P_n) in accordance with a disclosed relation formula that uses a ratio of flow path resistances on an upstream side and a downstream side of a branch point to the nozzle in an ink flow path.

CITATION LIST

Patent Literature

Patent Document 1: JP 5728148B

SUMMARY OF INVENTION

Technical Problem

Unfortunately, the relation formula of P_1 , P_2 , and P_n disclosed in Patent Document 1 is established only in a flow path structure having no branch in an ink flow path from a pressure source (P_1) on an upstream side to a pressure source (P_2) on a downstream side, as illustrated in FIG. 4.

In one example, the relation formula of P_1 , P_2 , and P_n disclosed in Patent Document 1 does not hold in a flow path structure in which a pressure source (P_1) on an upstream side and a pressure source (P_2) on a downstream side are connected by an ink flow path that branches into a flow path (flow path resistances R_4 and R_5) passing through a nozzle "N" and a flow path (flow path resistance R_3) bypassing the nozzle "N", as illustrated in FIG. 5.

As described above, the method disclosed in Patent Document 1 requires obtaining a relation formula of P_1 , P_2 , and P_n for each of inkjet heads having different flow path structures.

The present invention has been made in view of the above-described problem in the conventional technique, and an object of the present invention is to enable easily maintaining an appropriate ink pressure in the vicinity of an opening of a nozzle, irrespective of a flow path structure, in an inkjet recording device.

Solution to Problem

A first aspect of the present invention for solving the problem described above provides an inkjet recording device including at least one inkjet head, a first pressure source, a second pressure source, and a controller. The inkjet head has a pressure chamber that communicates with a nozzle and is configured to eject ink from the nozzle. The ink communicates with the pressure chamber.

10 The first pressure source is configured to adjust energy per unit volume of the ink so that the ink generates "energy per unit volume" $P_1(\text{Pa})$, relative to static ink at the atmospheric pressure at a position having a height of an opening of the nozzle.

15 The second pressure source is configured to adjust energy per unit volume of the ink so that the ink generates "energy per unit volume" $P_2(\text{Pa})$, relative to static ink at the atmospheric pressure at the position having the height of the opening of the nozzle.

20 The first pressure source, the pressure chamber, and the second pressure source are connected in this order by a flow path.

25 Assuming that a pressure loss occurring from the first pressure source to the nozzle due to a circulation flow rate is ΔP_a , a constant of proportionality of a differential pressure (P_1-P_2) and ΔP_a is "a", and an appropriate pressure that is generated in the vicinity of the opening of the nozzle is P_n , the controller is configured to control pressure so that a relation $P_2=\{P_n-(1-a)P_1\}/a$ is established.

30 According to a second aspect of the present invention, in the inkjet recording device according to the first aspect, assuming that a limit value of P_1 at which the ink overflows from the nozzle during non-circulation due to the differential pressure (P_1-P_2) being 0(Pa) is P_{11} , and a limit value of P_1 at which the ink overflows from the nozzle during circulation due to the differential pressure (P_1-P_2) being any value other than 0 is P_{12} , a relation $\Delta P_a=|P_{12}-P_{11}|$ is established.

35 According to a third aspect of the present invention, in the inkjet recording device according to the first or the second aspect, assuming that a pressure loss occurring at the time of ejecting the ink from the nozzle is ΔP_b , the diameter of the nozzle is "d", and the surface tension of the ink is σ , P_n is a value less than 0(Pa) and greater than a value obtained from $-(4\sigma/d-a(P_1-P_2)-\Delta P_b)$.

40 According to a fourth aspect of the present invention, in the inkjet recording device according to the third aspect, assuming that a limit value of P_1 at which air bubbles are caught from the nozzle at the time of non-ejection during circulation is P_{13} , and a limit value of P_1 at which air bubbles are caught from the nozzle at the time of ejection during circulation is P_{14} , a relation $\Delta P_b=|P_{14}-P_{13}|$ is established.

45 A fifth aspect of the present invention provides a method for manufacturing an inkjet recording device. The inkjet recording device includes at least one inkjet head, a first pressure source, and a second pressure source. The inkjet head has a pressure chamber that communicates with a nozzle and is configured to eject ink from the nozzle. The ink communicates with the pressure chamber.

50 The first pressure source is configured to adjust energy per unit volume of the ink so that the ink generates "energy per unit volume" $P_1(\text{Pa})$, relative to static ink at the atmospheric pressure at a position having a height of an opening of the nozzle.

55 The second pressure source is configured to adjust energy per unit volume of the ink so that the ink generates "energy

per unit volume" $P_2(\text{Pa})$, relative to static ink at the atmospheric pressure at the position having the height of the opening of the nozzle.

The first pressure source, the pressure chamber, and the second pressure source are connected in this order by a flow path. The method includes assuming that a pressure loss occurring from the first pressure source to the nozzle due to a circulation flow rate is ΔP_a , calculating a constant of proportionality "a" of a differential pressure ($P_1 - P_2$) and ΔP_a . The method also includes, assuming that an appropriate pressure that is generated in the vicinity of the opening of the nozzle is P_n , designing so that a relation $P_2 = \{P_n - (1-a)P_1\}/a$ is established.

In a sixth aspect of the present invention, the method for manufacturing the inkjet recording device according to the fifth aspect also includes, assuming that a limit value of P_1 at which the ink overflows from the nozzle during non-circulation due to the differential pressure ($P_1 - P_2$) being 0(Pa) is P_{11} , and a limit value of P_1 at which the ink overflows from the nozzle during circulation due to the differential pressure ($P_1 - P_2$) being any value other than 0 is P_{12} , determining P_{11} and P_{12} by varying the values P_1 and P_2 while maintaining the differential pressure ($P_1 - P_2$) at any value, calculating ΔP_a from a relation $\Delta P_a = |P_{12} - P_{11}|$, and calculating "a" from a correlation of the differential pressure ($P_1 - P_2$) and ΔP_a .

In a seventh aspect of the present invention, the method for manufacturing the inkjet recording device according to the fifth or the sixth aspect further includes, assuming that a pressure loss occurring at the time of ejecting the ink from the nozzle is ΔP_b , the diameter of the nozzle is "d", and the surface tension of the ink is σ , setting P_n at a value less than 0(Pa) and greater than a value obtained from $-(4\sigma/d - a(P_1 - P_2) - \Delta P_b)$.

In an eighth aspect of the present invention, the method for manufacturing the inkjet recording device according to the seventh aspect further includes, assuming that a limit value of P_1 at which air bubbles are caught from the nozzle at the time of non-ejection during circulation is P_{13} , and a limit value of P_1 at which air bubbles are caught from the nozzle at the time of ejection during circulation is P_{14} , determining P_{13} and P_{14} by varying the values P_1 and P_2 while maintaining the differential pressure ($P_1 - P_2$) at any value other than 0 and calculating ΔP_b from a relation $\Delta P_b = |P_{14} - P_{13}|$.

Advantageous Effects of Invention

The present invention enables easily maintaining an appropriate ink pressure in the vicinity of an opening of a nozzle, irrespective of a flow path structure, in an inkjet recording device.

BRIEF DESCRIPTION OF DRAWINGS

FIG. 1 is a schematic diagram illustrating main components of an inkjet recording device according to an embodiment of the present invention.

FIG. 2 is a graph according to the embodiment of the present invention, illustrating a proportional relationship of a differential pressure between a first pressure source and a second pressure source and a pressure loss generated from the first pressure source to a nozzle due to a circulation flow rate.

FIG. 3 is a pressure chart according to the embodiment of the present invention.

FIG. 4 is a schematic diagram illustrating an inkjet flow path structure of a conventional example.

FIG. 5 is a schematic diagram illustrating an inkjet flow path structure of another conventional example.

DESCRIPTION OF EMBODIMENTS

Hereinafter, an embodiment of the present invention will be described with reference to the drawings. The following 10 describes an embodiment of the present invention and is not intended to limit the present invention.

As illustrated in FIG. 1, an inkjet recording device 1 of this embodiment includes an inkjet head 10, an ink supply unit 20, a controller 30, and a conveyance drive unit 40.

The inkjet head 10 includes a nozzle "N" and a pressure chamber 11 that communicates with the nozzle "N". The inkjet head 10 performs operation such as recording operation for recording an image, etc., on a recording medium by 20 ejecting ink from the nozzle "N". The ink communicates with the pressure chamber 11 and is ejected by the action of a drive element, such as a piezoelectric element. At least one inkjet head 10 is provided, but a plurality of inkjet heads 10 25 may be provided. The pressure that is generated in the vicinity of the opening of the nozzle "N" is represented as "Pn".

The conveyance drive unit 40 moves a target recording medium on which an image is to be recorded by the inkjet head 10, relative to the nozzle "N" of the inkjet head 10.

The ink supply unit 20 includes a first pressure source 21 and a second pressure source 22.

The first pressure source 21 communicates with a first flow path 12 and adjusts energy per unit volume of ink so that the ink will generate "energy per unit volume" $P_1(\text{Pa})$, 35 relative to static ink at the atmospheric pressure at a position having the height of the opening of the nozzle "N".

The second pressure source 22 communicates with a second flow path 13 and adjusts energy per unit volume of ink so that the ink will generate "energy per unit volume" 40 $P_2(\text{Pa})$, relative to static ink at the atmospheric pressure at a position having the height of the opening of the nozzle "N".

Specifically, the first pressure source 21 and the second pressure source 22 include ink chambers that are positioned 45 at a predetermined height relative to the position having the height of the opening of the nozzle "N". The first pressure source 21 and the second pressure source 22 also include components such as an ink tank, a pump, a control valve, and a sensor, for controlling inflow and outflow of ink to the ink chamber and controlling pressure applied to a liquid surface in the ink chamber.

The controller 30 includes a central processing unit (CPU) 31 and a storage 32 and collectively controls various operations of the inkjet recording device 1. The operations of the 50 inkjet recording device 1 to be controlled include supply and circulation of ink, image recording operation, and maintenance operation of the inkjet head 10. The CPU 31 executes a control process by performing various arithmetic calculations. The storage 32 includes, for example, a random access memory (RAM) and a nonvolatile memory. The RAM provides a working memory space to the CPU 31 and stores temporary data. The nonvolatile memory stores and holds various control programs and setting data. The nonvolatile memory is, for example, a flash memory, and may include 55 a hard disk drive (HDD).

The flow path structure illustrated in FIG. 1 is an example and has the following configuration.

The first pressure source 21 is connected to the pressure chamber 11 via the first flow path 12 and a fourth flow path 15. The pressure chamber 11 is connected to the second pressure source 22 via a fifth flow path 16 and a second flow path 13. The connection point between the first flow path 12 and the fourth flow path 15 and the connection point between the second flow path 13 and the fifth flow path 16 are connected by a third flow path 14 without passing the pressure chamber 11.

Assuming that the flow rate in the third flow path 14 is Q_1 , and the flow rate in the fourth flow path 15 and the fifth flow path 16 is Q_2 , the flow rate in each of the first flow path 12 and the second flow path 13 is (Q_1+Q_2) . Flow path resistances R_1 to R_5 of the first to the fifth flow paths are illustrated in the drawing. Note that each of the first flow path 12 and the second flow path 13 includes a head outside flow path that connects the head 10 and the pressure source (the same applies to the case in FIGS. 4 and 5).

Meanwhile, in the present invention, for the purpose of maintaining P_n at an appropriate pressure, these flow path resistances R_1 to R_5 are not used, and the flow path structure is not limited to that described above. For example, the present invention can be applied to various flow path structures in addition to the flow path structure illustrated in FIG. 4.

In order to maintain P_n at an appropriate pressure, the controller 30 controls the pressures P_1 and P_2 as described below.

That is, assuming that a pressure loss occurring from the first pressure source 21 to the nozzle "N" due to a circulation flow rate is ΔP_a , a constant of proportionality of a differential pressure (P_1-P_2) and ΔP_a is "a", and an appropriate pressure that is generated in the vicinity of the opening of the nozzle "N" is P_n , the controller 30 controls pressure so as to establish a relation $P_2=\{P_n-(1-a)P_1\}/a \dots (3)$. The controller 30 variably controls the values P_1 and P_2 to make them different values, in accordance with the formula (3). The controller 30 variably controls the values P_1 and P_2 that satisfy the relation of the formula (3), between values P_1 and P_2 for a high flow speed due to a high differential pressure (P_1-P_2) and values P_1 and P_2 for a low flow speed due to a low differential pressure (P_1-P_2) , while P_n is in an appropriate range.

As to P_n , P_1 is reduced due to the pressure loss ΔP_a , and thus, the following formula (1) is established.

$$P_n=P_1-\Delta P_a \quad (1)$$

Definition in assuming that a constant of proportionality of the differential pressure (P_1-P_2) and ΔP_a is "a" is represented as the formula (2).

$$\Delta P_a=a(P_1-P_2) \quad (2)$$

The formula (2) is substituted into the formula (1).

$$P_n=P_1-a(P_1-P_2)=(1-a)P_1+aP_2$$

This formula is further modified into the following formula:

$$P_2=\{P_n-(1-a)P_1\}/a \quad (3)$$

The ΔP_a has the following relation.

That is, assuming that a limit value of P_1 at which ink overflows from the nozzle "N" during non-circulation due to the differential pressure (P_1-P_2) being 0(Pa) is P_{11} , and a limit value of P_1 at which ink overflows from the nozzle "N" during circulation due to the differential pressure (P_1-P_2) being any value other than 0 is P_{12} ,

$$\Delta P_a=|P_{12}-P_{11}|$$

With the use of this relation, the constant of proportionality "a" of the differential pressure (P_1-P_2) and ΔP_a is obtained by trials, such as experiments. FIG. 2 illustrates a graph showing the proportional relationship between the differential pressure (P_1-P_2) and the pressure loss ΔP_a .

The P_{11} and P_{12} are determined by varying the values P_1 and P_2 while maintaining the differential pressure (P_1-P_2) at any value.

When P_1 is increased (and P_2 is also increased so as to have the same value as P_1) while maintaining the differential pressure (P_1-P_2) at 0, ink reaches the limit of overflow from the nozzle "N". Thus, the value P_1 at this time is used as P_{11} .

When P_1 is increased while maintaining the differential pressure (P_1-P_2) at each of multiple any values other than 0, ink reaches the limit of overflow from the nozzle "N". Thus, the value P_1 at this time is used as P_{12} .

The pressure losses ΔP_a respectively corresponding to a plurality of differential pressures (P_1-P_2) are calculated from the formula (4), and the constant of proportionality "a" is calculated from a correlation of these plurality of pairs of the differential pressure (P_1-P_2) and ΔP_a .

In the recording operation, ink is ejected from the nozzle "N" during circulation when the differential pressure (P_1-P_2) is any value other than 0.

Assuming that a pressure loss occurring at the time of ejecting ink from the nozzle "N" is ΔP_b , the diameter of the nozzle "N" is "d", and the surface tension of the ink is σ , the appropriate pressure P_n is a value less than 0(Pa) and greater than a value obtained from $-(4\sigma/d-a(P_1-P_2)-\Delta P_b) \dots (5)$.

In addition, assuming that a limit value of P_1 at which air bubbles are caught from the nozzle "N" at the time of non-ejection during circulation is P_{13} , and a limit value of P_1 at which air bubbles are caught from the nozzle "N" at the time of ejection during circulation is P_{14} , a relation $\Delta P_b=|P_{14}-P_{13}| \dots (6)$ is established.

With the use of this relation, ΔP_b is obtained by trials, such as experiments.

The P_{13} and P_{14} are determined by varying the values P_1 and P_2 while maintaining the differential pressure (P_1-P_2) at any value other than 0.

First, when ejection from the nozzle "N" is not performed, the values of P_1 and P_2 are varied while maintaining the differential pressure (P_1-P_2) at any value other than 0, to increase the degree of intake of the outside air from the nozzle "N". Then, a limit of occurrence of catching air bubbles from the nozzle "N" comes. The value of P_1 at this time is used as P_{13} .

Moreover, when ejection from the nozzle "N" is performed, the values of P_1 and P_2 are varied while maintaining the differential pressure (P_1-P_2) at any value other than 0, to increase the degree of intake of the outside air from the nozzle "N" in conjunction with reaction of ejection operation. Then, a limit of occurrence of catching air bubbles from the nozzle "N" comes. The value of P_1 at this time is used as P_{14} .

The ΔP_b is calculated from the formula (6).

After ΔP_b is calculated, the value of the formula (5) is determined, whereby the range of the appropriate pressure P_n is obtained.

The controller 30 controls pressure in accordance with the range of the appropriate pressure P_n , which is thus determined, and the formula (3). As a result, a meniscus that is formed at the opening of the nozzle "N" is suitably maintained.

A more detailed description will be made with reference to the pressure chart in FIG. 3.

The vertical axis illustrated in FIG. 3 shows a magnitude of P1. The P1 is assumed to be of an ink supply side. The vertical bar B1 on the right side of the vertical axis shows a pressure range of each state and a boundary (limit value) of the pressure range in the condition in which the differential pressure (P1-P2) is 0 (kPa). The vertical bar B2 on the most right side shows a pressure range of each state and a boundary (limit value) of the pressure range in the condition in which the differential pressure (P1-P2) is ΔP_d (kPa). Note that $\Delta P_d \neq 0$.

In the range over the pressure value P11 in the bar B1, ink can overflow from the nozzle "N". In the range over the pressure value P12 in the bar B2, ink can overflow from the nozzle "N". The difference between P12 and P11 corresponds to the pressure loss ΔP_a that occurs from the first pressure source 21 to the nozzle "N" due to the circulation flow rate.

In the bar B1 in which the differential pressure (P1-P2) is 0 (kPa), $P1=P2=P_n=0$ (kPa), that is, ink can overflow from the nozzle "N" at the atmospheric pressure at the position having the height of the opening of the nozzle "N".

In the bar B2 in which the differential pressure (P1-P2) is ΔP_d (kPa), due to flow of ink, there is a pressure loss ΔP_a from P1 to P_n .

The pressure loss ΔP_a can be calculated from the difference between the pressures P11 and P12 at the same phenomenon in which ink overflows from the nozzle "N", in the bars B1 and B2.

The pressure value P13 in the bar B2 corresponds to a limit value (static meniscus braking pressure), and air bubbles are caught if P1 falls below this limit value while ink is not ejected.

The pressure value P14 in the bar B2 corresponds to a limit value (dynamic meniscus braking pressure), and air bubbles are caught at the time of ejecting ink if P1 falls below this limit value.

Thus, the difference between P14 and P13 corresponds to the pressure loss ΔP_b that occurs at the time of ejecting ink from the nozzle "N".

It is necessary to set P1 in the range of P12 to P14 in order to prevent overflow of ink from the nozzle "N" and to prevent intake of air bubbles although ink is ejected, in image recording operation. In this range, a meniscus that is formed at the opening of the nozzle "N" is maintained by the pressure $4\sigma/d$ due to the surface tension, although the pressure losses ΔP_a and ΔP_b occur.

Thus, the appropriate pressure P_n is less 0(Pa) and greater than the value obtained from the formula (5).

In manufacturing an inkjet recording device, the formula (3) is used after the constant of proportionality "a" and the appropriate pressure P_n are calculated as described above, and design is performed so that the relation of the formula (3) will be established. The constant of proportionality "a" does not depend on physical properties of ink on the condition that the flow path structure is the same. In consideration of this, the constant of proportionality "a" should be examined at least once with respect to the same type of inkjet heads having the same flow path structure.

The pressure chart illustrated in FIG. 3 differs depending on the setting of the differential pressure (P1-P2) during image recording operation and on physical properties of ink, and therefore, the appropriate pressure P_n is calculated for each of these conditions.

An inkjet recording device including a controller that has a control function for variably controlling P1, P2, and P_n while maintaining the relation of the formula (3), may be manufactured, or an inkjet recording device including an ink

supply unit that moves so that the relation of the formula (3) will be established during operation, may be manufactured.

As described above, this embodiment enables easily maintaining an appropriate ink pressure in the vicinity of an opening of a nozzle, irrespective of a flow path structure, in an inkjet recording device.

INDUSTRIAL APPLICABILITY

10 The present invention can be used in inkjet recording devices.

REFERENCE SIGNS LIST

1 inkjet recording device

10 inkjet head

20 ink supply unit

21 first pressure source

22 second pressure source

30 controller

40 conveyance drive unit

N nozzle

The invention claimed is:

1. An inkjet recording device comprising:

at least one inkjet head having a pressure chamber that communicates with a nozzle and being configured to eject ink from the nozzle, the ink communicating with the pressure chamber;

a first pressure source configured to adjust energy per unit volume of the ink so that the ink generates "energy per unit volume" $P_1(Pa)$, relative to static ink at an atmospheric pressure at a position having a height of an opening of the nozzle;

a second pressure source configured to adjust energy per unit volume of the ink so that the ink generates "energy per unit volume" $P_2(Pa)$, relative to static ink at an atmospheric pressure at the position having the height of the opening of the nozzle; and

a hardware processor, wherein

the first pressure source, the pressure chamber, and the second pressure source are connected in this order by a flow path,

assuming that a pressure loss occurring from the first pressure source to the nozzle due to a circulation flow rate is ΔP_a , a constant of proportionality of a differential pressure (P1-P2) and ΔP_a is "a", and an appropriate pressure that is generated in a vicinity of the opening of the nozzle is P_n , the hardware processor is configured to control pressure so that a relation $P_2=\{P_n-(1-a)P_1\}/a$ is established.

2. The inkjet recording device according to claim 1, wherein, assuming that a limit value of P1 at which the ink overflows from the nozzle during non-circulation due to the differential pressure (P1-P2) being 0(Pa) is P11, and a limit value of P1 at which the ink overflows from the nozzle during circulation due to the differential pressure (P1-P2) being any value other than 0 is P12, a relation $\Delta P_a=|P_{12}-P_{11}|$ is established.

3. The inkjet recording device according to claim 1, wherein, assuming that a pressure loss occurring at the time of ejecting the ink from the nozzle is ΔP_b , a diameter of the nozzle is "d", and a surface tension of the ink is σ , P_n is a value less than 0(Pa) and greater than a value obtained from $-(4\sigma/d-a(P_1-P_2)-\Delta P_b)$.

4. The inkjet recording device according to claim 3, wherein, assuming that a limit value of P1 at which air bubbles are caught from the nozzle at the time of non-

ejection during circulation is P13, and a limit value of P1 at which air bubbles are caught from the nozzle at the time of ejection during circulation is P14, a relation $\Delta P_b = |P14 - P13|$ is established.

5. A method for manufacturing an inkjet recording device, the inkjet recording device comprising:
 at least one inkjet head having a pressure chamber that
 communicates with a nozzle and being configured to
 eject ink from the nozzle, the ink communicating with
 the pressure chamber;
 a first pressure source configured to adjust energy per unit
 volume of the ink so that the ink generates "energy per
 unit volume" P1(Pa), relative to static ink at an atmo-
 spheric pressure at a position having a height of an
 opening of the nozzle; and
 10 a second pressure source configured to adjust energy per
 unit volume of the ink so that the ink generates "energy
 per unit volume" P2(Pa), relative to static ink at an
 atmospheric pressure at the position having the height
 of the opening of the nozzle,
 the first pressure source, the pressure chamber, and the
 second pressure source being connected in this order by
 15 a flow path,
 the method comprising:
 assuming that a pressure loss occurring from the first
 pressure source to the nozzle due to a circulation flow
 rate is ΔP_a , calculating a constant of proportionality "a"
 of a differential pressure (P1-P2) and ΔP_a ; and
 assuming that an appropriate pressure that is generated in
 20 a vicinity of the opening of the nozzle is Pn,
 designing so that a relation $P2 = \{Pn - (1-a)P1\}/a$ is estab-
 lished.

10

6. The method for manufacturing the inkjet recording device according to claim 5, further comprising:

assuming that a limit value of P1 at which the ink
 overflows from the nozzle during non-circulation due
 to the differential pressure (P1-P2) being 0(Pa) is P11,
 and a limit value of P1 at which the ink overflows from
 the nozzle during circulation due to the differential
 pressure (P1-P2) being any value other than 0 is P12,
 determining P11 and P12 by varying the values P1 and P2
 while maintaining the differential pressure (P1-P2) at
 any value;
 calculating ΔP_a from a relation $\Delta P_a = |P12 - P11|$; and
 calculating "a" from a correlation of the differential
 pressure (P1-P2) and ΔP_a .

7. The method for manufacturing the inkjet recording device according to claim 5, further comprising, assuming that a pressure loss occurring at the time of ejecting the ink from the nozzle is ΔP_b , a diameter of the nozzle is "d", and a surface tension of the ink is σ ,

setting Pn at a value less than 0(Pa) and greater than a
 value obtained from $-(4\sigma/d - a(P1 - P2) - \Delta P_b)$.

8. The method for manufacturing the inkjet recording device according to claim 7, further comprising:

assuming that a limit value of P1 at which air bubbles are
 caught from the nozzle at the time of non-ejection
 during circulation is P13, and a limit value of P1 at
 which air bubbles are caught from the nozzle at the time
 of ejection during circulation is P14,
 determining P13 and P14 by varying the values P1 and P2
 while maintaining the differential pressure (P1-P2) at
 any value other than 0; and
 calculating ΔP_b from a relation $\Delta P_b = |P14 - P13|$.
